UNITED STATES PATENT OFFICE.

GEORGE R. AINSWORTH, OF GREAT NECK, NEW YORK.

DESIGN FOR AN ELECTRIC-LIGHT FIXTURE.

50,332.

Specification for Design.

Patented Feb. 20, 1917.

Application filed October 6, 1916. Serial No. 124,200. Term of patent 3½ years.

To all whom it may concern:

Be it known that I, GEORGE R. AINSWORTH, a citizen of the United States, and a resident of Great Neck, Nassau county, New York, have invented a new, original, and ornamental Design for Electric-Light Fixtures, of which the following is a specification, reference being had to the accompanying drawing, in which the figure shows a front elevation of a fixture embodying my invention.

The design comprised in this invention consists in an electric light fixture having a back plate comprising a central portion from which extend flattened balusters designed according to an eighteenth century rendering, and from which central portion extend a plurality of arms to carry lights.

What I claim is:

The ornamental design for an electric light fixture as shown and described.

GEORGE R. AINSWORTH.
